[57] CLAIM

The ornamental design for a shoe pocket, as shown and described.

DESCRIPTION

FIG. 1 is a perspective view of a shoe pocket showing my new design;

FIG. 2 is a perspective view of a second embodiment thereof;

FIG. 3 is a front elevational view of the first embodiment thereof;

FIG. 4 is a right side elevational view with the left side being a mirror image thereof;

FIG. 5 is a top view thereof;

FIG. 6 is a bottom view thereof;

FIG. 7 is a rear elevational view thereof;

FIG. 8 is a front elevational view of the second embodiment thereof;

FIG. 9 is a right side elevational view with the left side being a mirror image thereof; and,

FIG. 10 is a bottom elevational view thereof.

The top view of the second embodiment is identical to the top view of the first embodiment. The broken line showing of a button and shoe in FIG. 1, a button in FIG. 3, and securing stitching for velcro in FIGS. 2 and 8 is for illustrative purposes only and forms no part of the claimed design.
